UNITED STATES PATENT OFFICE.

JOHANN THEODOR JOSEPH SEIFERT, OF DRESDEN-NEUSTADT, GERMANY, ASSIGNOR
TO NEUE BERLINER MESSINGWERKE WILHELM BORCHERT, JR., OF BERLIN, GER-
MANY, A FIRM.

HYDRAULIC METAL-PRESS.

974,195.

Specification of Letters Patent. Patented Nov. 1, 1910.

Application filed November 16, 1909. Serial No. 528,407.

To all whom it may concern:

Be it known that I, JOHANN THEODOR JOSEPH SEIFERT, workmaster, a subject of the King of Prussia, and resident of Wildermannstrasse 53, Dresden-Neustadt, Germany, have invented certain new and useful Improvements in and Relating to Hydraulic Metal-Presses, of which the following is a specification.

- 10 This invention relates to improvements in hydraulic presses for the manufacture of tubes or rods from hollow or solid blocks. In presses of this kind for practical reasons it is not possible to drive the press plunger sufficiently forward to enable all the material to be forced out of the receptacle. Owing to this a dead-head remains on the pressed tube or rod and this has subsequently to be cut away for the purpose of removing the work from the die. In order to render this cutting possible it has heretofore been usual to remove the die which is centrally fixed to the receptacle itself from this receptacle together with the work last pressed.
- 20 After the removal of the dead-head the die is again inserted and fixed in the receptacle. This method of operation necessitated the exclusive attention and services of two workmen whose time were fully occupied in effecting the withdrawal and reinsertion of the die. The continual withdrawal of the die from its centering entailed the further defect that owing to wear the centering soon became inaccurate thereby very prejudicially effecting the quality of the work. If the workmen entirely omitted to ascertain each time before reinserting the die whether any foreign body such as shavings of the material or the like had penetrated the centering such foreign bodies frequently caused the centering to be entirely inaccurate so that numerous "wasters" were formed.

The present invention has for its object to obviate these defects and in accordance therewith the die is not centrally fixed on the receptacle but on a separate auxiliary hydraulic piston open at its rear end and by means of which it is pressed against the receptacle. With this arrangement the die need not be removed from its fitting after the pressing operation but the auxiliary piston and the die are merely withdrawn from the receptacle and the work removed after the deadhead has been cut away, where-

upon the die and the receptacle are again 55 united.

It is true that it has already been proposed to sever the deadhead in the receptacle itself by means of a severing ring fixed to the pressure surface thereby rendering it 60 unnecessary to remove the die each time; but this manner of procedure has proved to be impractical, and even if it were practical would present the defect that the removal of the deadhead from the receptacle would 65 be very difficult to perform. On the other hand in accordance with the improved device the mechanical severing of the deadhead may be very readily effected for the reason that after every stroke of the press 70 the die is lifted from the receptacle so that the severed deadhead is allowed to fall freely.

In accordance with what has been stated above the invention mainly consists in the 75 combination of two features that is to say the hydraulically displaced counter-piston and the ejection of the work on the side of the hollow auxiliary piston opposite to the main piston for which purpose the auxiliary 80 piston must be open. The combination of these two features results in a more compact and reliable construction of the press, reduces the labor necessary and economizes the consumption of water under pressure. 85 The new device has the further arrangement that the receptor, independently from the main piston, is movable to the extent of the depth of the receiving chamber and is provided with a corresponding hydraulic auxiliary 90 feeding mechanism. The hydraulic auxiliary feeding mechanism in itself is known, but in the older machines was confined within narrow limits, in conformity with its object of releasing the matrix from 95 the receptor the first time. Against this, in the new device, the task of the hydraulic auxiliary feeding mechanism of the receptor, which is made to have a proportionately long stroke necessitated by the arrangement 100 of the afore-mentioned hydraulic auxiliary piston, consists of making possible an easy exchange of the press-rings and press-spur without throwing off the matrix, and, further, creating optionally a large intermediate space between the main piston and the receptor, or between the receptor and the matrix, which is important not alone for 105

the optional feeding of the receptor from the side of the piston or the matrix, but also for the making of repairs and other work on the machine. Furthermore, the 5 hydraulic auxiliary feeding mechanism of the receptor, in the new press, makes it possible, after the insertion of the piece to be worked from the side of the piston while the main piston of the press remains stationary, 10 to move the receptor so far against the said piston that the pressure surface touches the block on the machine, after which—and not sooner—the press piston is started. This has the advantage that much less press-water 15 is consumed than if the main piston had also to perform the first inactive part of the stroke. Of course, the new machine can also work in such a manner that the receptor, in its end position toward the side of 20 the piston, remains permanently stationary and the matrix is moved only once, backward and forward at each operation, by means of its auxiliary piston.

An embodiment of the invention is illustrated by way of example diagrammatically in longitudinal section in the accompanying drawing.

The press cylinder is marked *a*. In it the 30 guide mandrel *b* is fixed by means of a collar *c* and wedge or key *d*. The guide mandrel *b* carries at its end the caliber mandrel *e* and serves as a central guide for the press piston *f*.

The stationary cross head *h* is connected 35 by means of longitudinal tie rods *g* with the stationary cylinder *a*. The receptacle *i* is guided on these rods *g* and is connected by means of the connecting rods *k* with the pistons *l* of smaller auxiliary hydraulic cylinders *m* provided on the cylinder casting *a*. The perforated block *n* is inserted in the bore of the receptacle *i* for the purpose of forming a tube for example. In the cross head *h* an auxiliary hydraulic cylinder *o* is 40 provided, the die *q* being centrally fitted in its hollow piston *p*. The front end of the die is conically constructed and when the die is displaced toward the receptacle by the piston *p* it enters a corresponding conical 45 cavity in the receptacle thereby forming a good and central joint.

An auxiliary hydraulic cylinder *r* is fixed to the cross head *h* and is provided with a piston *s* which carries at its lower end a 50 knife *t* the cutting edge of which lies in the same plane as the end face of the die. This knife serves to sever the dead-head in the manner hereinafter explained. The pressure surface of the main piston is marked *u*.

60 The apparatus operates in the following manner:—With the press piston *f* drawn back the receptacle *i* is moved away from it to such an extent that the end of the caliber mandrel *e* is distant from the mouth of the 65 receptacle somewhat more than the height

of the block *n* to be inserted whereupon the latter is introduced into the bore in the receptacle. At this stage the receptacle *i* is moved forward by means of the auxiliary piston *l* until the pressing annular face *u* of the main piston contacts with the end 70 face of the block *n*. Simultaneously or successively thereto pressure is supplied to the piston *p* which moves in the left hand direction so that at the end of the stroke the die *q* 75 bears firmly against the receptacle as shown in the position of the machine represented in the drawing. The conduits leading to the auxiliary cylinders *m* and *o* are then closed and the piston *f* is pressed forward against 80 the block *n* whereby the pressed tube passes through the hollow piston *p*.

When the pressing operation is completed the piston *p* of the cylinder *o* and with it the die *q* is displaced from the receptacle *n*. As 85 soon as this has taken place pressure is supplied to the auxiliary cylinder *r* resulting in a downward movement of the piston *s* and knife *t* and the consequent severing of the deadhead. The finished work can then be 90 completely withdrawn from the die and the hollow piston *p*. When the pistons *f* *l* *p* and *s* move back the machine is ready for a further pressing operation.

With the arrangement of the machine here 95 illustrated the press mandrel *e* is both interchangeable and very easy of access.

What I claim and desire to secure by Letters Patent of the United States is:—

1. In a hydraulic press for the manufacture of tubes or rods from hollow or solid blocks, a main pressure cylinder and piston and an auxiliary cylinder and piston; a die supported by the piston of said auxiliary cylinder, said auxiliary piston being open 100 at both ends with the axis thereof located in alinement with the axis of the piston of the main pressure cylinder in order that the finished article may be ejected through the hollow piston of said auxiliary cylinder. 105

2. A hydraulic press of the character indicated provided with a press cylinder, and an auxiliary cylinder having a hollow piston; together with a die held in operative position within such hollow piston. 110

3. A hydraulic press for the manufacture of tubes or rods from hollow or solid blocks, embracing a main piston and an auxiliary tubular piston; in combination with a die located within said tubular piston, and a cutter operatively connected with means for causing it to sever the deadhead from the work. 115

4. A hydraulic press of the character indicated provided with a press cylinder, an auxiliary cylinder, and a block holding receptacle, said block holding receptacle being operatively connected with secondary or additional cylinders. 120

5. A hydraulic press of the character indi- 125

cated provided with a press cylinder, an auxiliary cylinder, and a block holding receptacle, said block holding receptacle being operatively connected with secondary hydraulic cylinders, the effective length of the stroke of the pistons of which is the same or substantially the same as the depth of the receptacle.

In testimony whereof I have hereunto set my hand in presence of two subscribing witnesses this second day of November 1909.

JOHANN THEODOR JOSEPH SEIFERT.
